UNITED STATES PATENT OFFICE.

FRANK MONROE DREIBELBIS, OF LOS ANGELES, CALIFORNIA.

DETACHABLE HORSE-FOOT PAD.

SPECIFICATION forming part of Letters Patent No. 431,717, dated July 8, 1890.

Application filed April 22, 1890. Serial No. 348,970. (No model.)

To all whom it may concern:

Be it known that I, FRANK MONROE DREIBELBIS, a citizen of the United States, residing at Los Angeles, in the county of Los Angeles and State of California, have invented a new and useful Detachable Horse-Foot Pad, of which the following is a specification.

My invention relates to pads for the bottoms of horses' feet.

10 The object of my invention is to provide a horse-foot pad which may be attached to the horse's foot when it is desired to speed him and detached from the foot when the horse is to be stabled.

15 My invention consists of the combination of a V-shaped or forked frame, means for securing the point or stem of the frame to the toe of the horse's shoe, a stiff pad-plate pivoted to one arm of such frame, such plate being slightly longer than the distance between the arms of the heel of the shoe and having its ends adapted for insertion between the shoe and the hoof, a pad secured to such plate, and means for securing the plate in and 25 releasing it from a position transverse to the axis of the frame.

The accompanying drawings illustrate my invention.

Figure 1 is a view of the under side of a 30 horseshoe with my improvement attached. Dotted lines show the pad and its plate turned in position for detachment. Fig. 2 is a view of the upper side of the shoe and attachment. Fig. 3 is a side elevation of the attachment. 35 Fig. 4 is a rear view of a horse's foot with shoe and pad attached, the shoe being in section on line x x, Fig. 1.

A is the V-frame, provided at its apex or point with a hook a to hook into a hole b in 40 the toe of the shoe B.

C is the transverse pad-plate, to which the pad D, of rubber or other suitable material, is secured. The pad-plate C is pivoted to one arm q of the frame A by a pivot d.

45 E is the locking-spring, which is secured at one end to the other arm h of frame A, and is bent at the other end to form the locking-lug e, which projects through a hole in

the frame and into the path of the locking-plate, so that when in position, as shown in 50 Fig. 3, the plate is locked from turning toward the toe. The frame is provided with the pad-plate-retaining hook i. The end of arm h is bent to form the hook or lug i, which is designed to engage with the rear edge of plate 55 C to prevent it from turning backward.

I believe the simplest means for securing the frame to the toe of the shoe are those shown, consisting of the hook adapted to hook into a hole in the shoe; but I do not desire to 60 be limited to such means.

In practice the pad is attached to the shoe by first hooking the hook a into the hole b, the pad-plate being turned diagonally across the frame, as suggested by dotted lines in 65 Fig. 1, so as to allow the rear end of the plate to be inserted into the groove ordinarily formed between the horse's hoof and the inner edge of the shoe. When the rear end of the plate has been thus inserted in such 70 groove near the heel, the other end is raised and inserted in such groove near the toe. The plate is then turned round until it is transverse to the frame, as shown in Figs. 1 and 2, care being had to insert the rear edge of the 75 plate into the bend of hook i. When the plate is pressed home, the lug e springs into place, as shown in Fig. 3, and locks the plate securely. To remove the pad, the lug e is pressed up out of the path of the plate, thus 80 leaving the plate free to be turned into the position shown in dotted lines, Fig. 1. Then the pad is free to be removed.

Rubber is preferable for the pad. The arms of the V-frame are made with reference to 85 the frog of the horse's foot, care being had that they do not touch the frog, which should rest only on the plate.

Now, having described my invention, what I claim as new, and desire to secure by Letters Patent, is—

1. The combination of the frame, means for securing the front of the frame to the toe of a horseshoe, the pad-plate pivoted to the frame and having its ends adapted for insertion between the shoe and the horse's hoof, a pad 95

secured to such plate, and means for locking the plate in and releasing it from a position transverse to the axis of the shoe.

2. The combination of the horseshoe provided with a hole at the toe, the forked frame provided at its point with a hook to hook into such hole, and having the pad-plate-retaining hook, the transverse pad-plate provided

with a pad and pivoted to one arm of the frame, and the locking-spring secured to the other arm of the frame and provided with the locking-lug.

FRANK MONROE DREIBELBIS.
